UNITED STATES PATENT OFFICE.

FREDERICK W. SULLIVAN, JR., WILLIAM J. MCGILL, AND HARRY L. WALKER, OF WHITING, INDIANA, ASSIGNORS TO STANDARD OIL COMPANY, OF WHITING, INDIANA, A CORPORATION OF INDIANA.

ART OF PRESSING WAX-CONTAINING OIL.

Application filed June 1, 1925. Serial No. 34,030.

The present invention relates to improvements in the art of filtering wax from hydro-carbon oils and will be fully understood from the following description, illustrated by the 5 accompanying drawing in which apparatus for carrying the invention into effect is diagrammatically illustrated.

In the drawing a wax filtering press is shown of the type more fully described in the 10 Fifield Patent No. 1,455,436, granted May 15, 1923. The numeral 5 indicates the press, the dotted lines 6 indicating the space occupied by the usual filter plates. Wax bearing oil is supplied to the press through the pipe 7. 15 A pipe 8, closed at its inner end 9 passes through the press, being supported therein by the plates 10. Openings 11 are provided in plates 10 around pipe 8 to permit free flow of oil, etc., through the press. A cylindrical 20 chamber 12 secured to the head of the press surrounds the pipe 8; and to it is connected the feed pipe 13 provided with two connections 14 and 15.

A small chamber 16 closes the end of pipe 25 8 outside the press, and a small pipe 17 extends through the chamber and through the greater part of the length of the pipe 8. The small pipe 17 is open at its end. A drain pipe 18 is also connected to chamber 16.

In accordance with the present invention, 30 the oil to be pressed, for example, paraffin distillate is chilled to the desired low temperature, say 50° F. or lower in accordance with the nature of the oil and the cold test of the 35 desired product, and is fed under pressure into the press, its wax content being collected therein. For example, if a low cold test is not desired in the oil product, the temperature during pressing may be 45 to 50° F. If 40 a low cold test oil is desired, the oil is preferably put through the press two or more times, the first filtration being at a temperature of 45 to 50° F. and the later filtrations at temperatures of 25° F. or lower.

In ordinary operation, the oil to be pressed 45 is forced through until the press is as nearly as possible filled with crude wax. This operation ordinarily requires thirty hours or longer, the pressure required being considerably increased in the later stages of operation and the size of the stream of oil product considerably diminishing after the first twelve or fourteen hours.

According to our method of operation, after

ten to fourteen hours of pressing, or when 55 the wax content of the cakes in the press reaches about 30 to 40%, the flow of oil through the feed pipe 7 is discontinued, and water is forced through the press, for example, through the pipes 15 and 13. Although cold water may be employed, we prefer to use water at a temperature of 75 to 110° F., and preferably about 100° F. The water employed is at a temperature below the melting point of the wax. The supply of water is 65 continued until a substantial quantity of the oil content of the wax in the press has been removed. This operation may require, ordinarily, from one half to one hour, and leaves the wax with an oil content of from 50 to 70 60%. By the end of the operation, the temperature of the press has been raised, usually to 60 to 90° F. After the supply of water has been discontinued, if desired, the press may be 75 filled with wax by supplying to it a high wax containing oil; preferably, one containing 50% or higher of oil. Thus, for example, slack wax, or sweat oil from the paraffin sweaters, may be employed, such products containing from 20 to 50% of wax and from 80 to 50% of 80 oil. This material is put into the press through the pipe 7, at a temperature at which at least part of the wax content is solid, suitably at 60 to 80°. The press is rapidly filled, the pressures required being in general above 300 85 pounds, and a final wax cake obtained containing from 20 to 40% of oil (generally about 35%) and having a melting point of about 112 to 116° F. The press may then be cleaned, for example, by the use of hot water supplied 90 through the pipe 14 after a central channel has been opened by the supply of steam through the pipe 17 to the pipe 8 extending into the press. Prior to cleaning, however, water at a temperature below the melting 95 point of the wax may again be forced through the press to remove oil from the wax, a reduction in oil content of 5 to 10% being thereby effected.

By operating in accordance with the present invention, the efficiency of the presses is very greatly increased, the time required for filling the presses being substantially reduced and the rate of flow of the oil, averaged over the entire pressing operation, being greatly increased.

We claim:

1. The method of filter pressing wax from

hydrocarbon oils which comprises forcing wax bearing oil through a filtering surface to build up a cake of wax thereon, and forcing through said wax cake water at a temperature 5 below the melting point of the wax, thereby removing oil therefrom.

2. The method of filter pressing wax from hydrocarbon oils which comprises forcing a chilled wax bearing oil through a filtering 10 surface to build up a cake of wax thereon, continuing the operation until the oil content of the cake is from 40 to 50%, and forcing water through the wax cake, the water being at a temperature of 75° to 110° F.
- 15 3. The method of operating a filter press for removing wax from wax bearing oils which comprises forcing chilled wax bearing oil through the press to build up wax cakes therein, discontinuing the flow of oil 20 and forcing through the wax in the press water at a temperature below the melting

point of the wax until a substantial portion of the oil in the wax in the press has been removed, and subsequently forcing a high wax containing oil through the press at a 25 temperature at which at least a part of the wax content is solid.

4. The method of operating a filter press for the removal of wax from hydrocarbon oils comprising forcing a chilled wax bearing oil through a press to deposit wax therein, discontinuing the operation while the oil content of the wax is from 40 to 50%, forcing water therethrough, the temperature of the water being about 100° F., to remove oil from 30 the wax in the press, and subsequently forcing through the press an oil containing 20% or higher of wax at a temperature at which at least a part of the wax content is solid.
